UNITED STATES PATENT OFFICE.

NOEL B. GINOCHIO, OF NEW YORK, N. Y., ASSIGNOR OF ONE-HALF TO ELIAS M. GREENE, OF SAME PLACE.

MAGNETO-ELECTRIC SIGNAL DEVICE.

SPECIFICATION forming part of Letters Patent No. 447,045, dated February 24, 1891.

Application filed May 9, 1890. Serial No. 351,173. (No model.)

To all whom it may concern:

Be it known that I, NOEL B. GINOCHIO, a citizen of the United States, residing at New York, in the county and State of New York, 5 have invented certain new and useful Improvements in Magneto-Electric Signal Devices, of which the following is a specification.

My invention relates to magneto-electric signal devices, and more especially to that class adapted to be used in connection with telephone and telegraph and other signal-transmitting lines, and it has for its object to provide an improved device whereby certain prearranged and distinctive signals can be given at will; and to these ends my invention consists in the construction, arrangement, and combination of the various devices, substantially as hereinafter more fully specified.

Referring to the accompanying drawings, wherein I have illustrated one and the preferred embodiment of my invention, Figure 1 is a plan view of the box, showing the door 25 open. Fig. 2 is a longitudinal section of the box. Fig. 3 is a diagrammatic representation showing the connections, and Fig. 4 is a diagram of the wheels.

The box A may be of any suitable or desirable construction, and is preferably provided with a door B, connected to one side of the box by hinges, which form a medium of connecting the circuits between the switch C, located on the cover, and the apparatus 35 located within the box. Secured in the box is a magneto-generator D, which may be of any suitable and preferred construction, although I have shown it as consisting of a number of curved permanent magnets d d, 40 connected by steps to pole-pieces d' d', between which rotates the armature mounted on the shaft E, as more particularly set forth in my application, Serial No. 339,119, filed February 4, 1890, and bearing on the end coils 45 of the armature is a plate or brush e, supported on the frame of the magnet, but insulated therefrom.

Supported in suitable bearings between the limbs of the magnet, as by brass or other 50 non-magnetic plates D', is a shaft F, carrying

a gear-wheel f, gearing with the pinion e' upon the shaft E, and also mounted on the shaft F is a pinion f', meshing with the gear f'', mounted on a stud or bearing secured to one of the plates D', and having a gear f''' engaging the pinion f' on the circuit-breaker shaft.

It is often desirable in devices of this kind to be enabled to send a predetermined signal made up of a certain number of smaller signals or impulses, so that any particular subscriber or other person may be called by simply rotating the armature, the circuits being properly arranged beforehand. In order that this may be done with accuracy and 65 that the timing of the elements of the signals may be regular with respect to one another, I provide a number of circuit-breakers, which are mounted upon the circuit-breaking shaft G, and are rotated through the 70 mechanism just described whenever the shaft is turned and a current generated. These circuit-breaking wheels may be of any desired construction; but I have shown them as consisting of disks having notches cut in 75 their periphery or projections extending therefrom, so that as they rotate they will present a greater or less surface to a brush or other connecting device, and the circuit will be closed to a greater or less extent and 80 a given number of times and in certain relations at each rotation of the disks. These disks are represented at H, and are numbered in the present instance 1, 2, 3, and 4, it being understood, of course, that there may be a 85 greater or less number of circuit-breakers, all mounted on the same shaft, according to the uses to which the apparatus is to be applied. A number of brushes H' are mounted on a suitable support, and their free ends are held 90 adjacent to the circuit-breakers and are adapted to make contact therewith as they rotate on the shaft.

It is desirable that the circuit-breaking shaft shall make one complete rotation in order that a complete signal may be sent, and should then be stopped, so that the operator will know when he has completed the signal. In order to do this I provide a suitable stopping device which shall control the rotation 100

of the shaft F and be in turn controlled by the rotation of the circuit-breaking shaft. While different means may be used for carrying this out, I have shown the shaft F as provided with a block or disk I, having two notches *i* on opposite sides. The shaft G is also provided with a disk J, having a single notch *j* in its periphery. Pivoted to the frame-work in some suitable position is an arm K, carrying a projection or stop *k*, normally engaging one of the notches *i* of the disk I, a spring L normally holding it in this locked position. The arm K is provided with an extension *k*², carrying a disk or wheel M, which is adapted to fit into the slot *j* in the periphery of the disk J, and a spring *m* surrounds the extension of the arm K and presses the disk M outward against the stop *m*'.

In Fig. 2 the machine is shown in its stationary position, and before the shaft can be rotated it is evident that some means must be provided for unlocking the device, and I have shown such means as consisting of a push-button N, projecting through the side 25 of the box and operating a bell-crank lever *n*, which impinges on the end *k*² of the rod, forcing the wheel M out of the notch in the disk J, and thereby also releasing the projection *k* from the notch *i* in the disk I. The shaft 30 F can then be rotated, operating the armature to produce the alternative currents, which are controlled by the circuits and switch hereinafter described, so that the particular signal may be sent over the line. When the circuit-breakers have completed one rotation, the wheel M falls into the notch *j* of the wheel J, and the projection *k* is thereby thrown into engagement with one of the notches *i* of the disk I, and the apparatus is locked against 35 further rotation. I provide the spring *m* for the purpose of allowing the disk or wheel M to yield slightly and to act somewhat as a break to prevent too quick or sudden stoppage of the parts, which might injure or otherwise disarrange them.

In order to prevent the shaft F being rotated backward, and thereby sending the signal in the reverse order from what was intended, I apply a ratchet-wheel O on the shaft 50 F, into which the pawl *o* engages, allowing free rotation in one direction, but preventing rotation in the opposite direction. Suitably mounted in the box is a polarized magnet P, operating the armature *p*, carrying the bell-hammer *p*', operating the bells in the usual way. The crank Q for driving the shaft is preferably provided with a sleeve Q', having a groove *q* engaging a pin *q*' on the shaft, and a spring *q*² tends to maintain the sleeve in 55 its outermost position, and when the crank is turned in the proper direction the sleeve will first travel around and inward on the shaft, compressing the spring *q*² and breaking the closed circuit, and then the shaft will be rotated, and when the crank Q is released it will 60 normally return to its outer position, as shown. Mounted on the cover of the box I have shown

a switch C, consisting of a switch-arm C', connected to a thumb-nut C² and having an index-arm C³ passing over a plate or other indicator C⁴. The arm C' is preferably of spring material, having a slight projection on its end, which may be beveled to fit the cups or other contact-pieces c c' c² c³ c⁴. These pieces are connected electrically with the 70 different circuit-breakers and with the frame of the machine, the conductors 1, 2, 3, and 4 being connected to the brushes of the respective circuit-breaking wheels, and the conductor 5 being connected to the frame of the 80 machine. The switch-arm is connected by a conductor 6 to the binding-post 7, which may lead to the ground, if desired. The binding-post 8 is connected to the line-wire 9, and thence by a conductor 10 to the coils of the 85 bell-magnet, from which a conductor 11 leads to the conductor 12, and thence to the brush e on the end of the armature-shaft. From the binding-post 7 a conductor 13 leads to a spring 14, normally bearing on the sleeve Q', 90 and another spring 15 bears upon the opposite side and is connected to the conductor 12. Thus the normal circuit when the machine is at rest is such that a signal from a distant station may operate the bell P, passing through the binding-post 8, conductor 10, bell-magnet conductors 11 and 12, through the springs 14 15, conductor 13, and binding-post 7 to ground. When, however, the generator is operated, the circuit between the 95 springs 14 and 15 is broken, as before described, and it will then be traced from ground through the binding-post 7, conductor 6, to the switch-arm C', to one of the contact-points, as c⁴, thence by the conductor 1 to the 100 brush, over the corresponding circuit-breaking wheel to the shaft of the same, and through the coils of the armature out through the brush e, through the conductors 11 and 12, coils of the magnets, conductor 10, binding-post 8, and line 9.

It will be understood that the circuit as last traced will be broken or closed in accordance with the construction and arrangement of the circuit-breaker wheel included therein. 115 These wheels are shown in one arrangement in Fig. 4. While many arrangements can be made, I have found it especially advantageous, when it is desired to call one of a number of subscribers, for instance, upon the same line, to cause a preliminary signal to be given, and when the machine is so adapted I provide each circuit-breaker with a projection X, which will cause a signal of the desired length to be given and will warn the hearer that a 120 call is to be sent. This is then followed with the desired number of projections Y, arranged in proper groups a proper distance apart to insure the signal given.

It will be seen from inspection that the 130 disk X, Fig. 4, will first send a preliminary signal and then a series of signals, which will be read and understood, as 1 2 3, and each time this disk is rotated this predetermined

system of signals will be sent, provided it is included in the circuit of the switch, and any one of the predetermined signals arranged on the circuit-breaking-wheels can be sent by moving the switch C', so as to complete the circuit through that particular circuit-wheel. If it is desired to send a continuous signal without interruption, I have arranged a circuit direct from the frame of the generator through the conductor 5 and the contact e, so that as long as the armature is rotated a continuous signal will be sent, the circuit being closed. It will thus be seen that by properly adjusting or constructing the circuit-breakers any number of signals can be sent, and they all being secured upon the same shaft they can be arranged so that the intervals between the signals are even and regular, and the listener can readily determine whether his particular call or signal has been made or not.

While I have thus described and illustrated what I consider the preferred embodiment of my invention, it is evident that many of the details of construction and arrangement of parts and circuits may be varied without departing from the general and essential features of the invention, and I therefore do not desire to limit myself to the precise mechanism shown and described.

30 What I claim is—

1. In a magneto-signal device, the combination, with the generator and driving-shaft therefor, of a series of circuit-controllers connected to said driving-shaft and a stop device for said driving-shaft controlled by the circuit-controllers, substantially as described.

2. In a magneto-signal device, the combination, with the generator and driving-shaft therefor, of a series of circuit-controllers connected to said driving-shaft, a stop device for said driving-shaft, devices connected with the circuit-controllers controlling said stop, and a pawl and ratchet preventing the backward turning of the driving-shaft, substantially as described.

45 3. In a magneto-signal device, the combination, with the generator and driving-shaft therefor, of circuit-controllers connected to said shaft, a stop device for said shaft controlled by the circuit-controllers, and a releasing device for releasing the said stop, substantially as described.

4. In a magneto-signal device, the combi-

nation, with the generator, of a driving-shaft therefor provided with a disk having cut-away portions, a circuit-controlling shaft also provided with a disk, and an arm provided with a detent engaging the driving-shaft disk and with a wheel engaging the circuit-controlling disk, substantially as described.

5. In a magneto-signal device, the combination, with the generator and the driving-shaft therefor having a disk provided with cut-away portions, of a circuit-controlling shaft provided with a disk having a slot, a pivoted arm having a detent engaging the driving-shaft disk, a wheel engaging the circuit-controlling disk, and a spring surrounding the arm and bearing on the wheel, substantially as described.

6. In a magneto-signal device, the combination, with the generator and circuit-controllers, of brushes connecting the circuit-controllers, a switch having a series of contacts connected with the brushes, and another contact connected with the frame of the machine, whereby a continuous or predetermined interrupted signal can be sent over the line by adjusting the switch, substantially as described.

7. In a magneto-signal device, the combination, with the generator, of a shaft driven thereby, a series of circuit-controlling disks mounted on the shaft, each circuit-controller being arranged to first send a preliminary signal and then an individual signal at each revolution of the disk, contact-brushes for the disks, circuits connected to said brushes, a circuit connected with the generator and with a switch, said switch being adapted to be connected to any one of the circuits of the circuit-controlling disks, and a stop device for the generator, controlled by the shaft carrying the circuit-controlling disks, whereby by moving the switch and rotating the generator any desired controlling-disk may be rotated through one complete revolution and operated to first send a preliminary signal and then a specific individual signal, substantially as described.

In testimony whereof I have signed my name to this specification in the presence of two subscribing witnesses.

NOEL B. GINOCHIO.
